UNITED STATES PATENT OFFICE

136,054

DESIGN FOR A COMBINATION PICTURE FRAME AND FLOWER CONTAINER

Richard Gottlieb Block, Los Angeles, Calif.

Application August 18, 1942, Serial No. 107,955

Term of patent 3½ years

To all whom it may concern:

Be it known that I, Richard Gottlieb Block, a citizen of the United States of America, residing in the city and county of Los Angeles, and the State of California, have invented a new, original, and ornamental Design for a Combination Picture Frame and Flower Container, of which the following is a specification, reference being had to the accompanying drawing, forming a part thereof.

Figure 1 is a front elevational view of a combination picture frame and flower container showing my new design; Figure 2 is a side elevational view thereof; and Figure 3 is a rear elevational view.

I claim:

The ornamental design for a combination picture frame and flower container, as shown.

RICHARD GOTTLIEB BLOCK.
